DOBBY LOOP FOR USE UPON LOOMS
 Lorenzo B. Wilkie, 205 Hutson St., Greenwood, S.C.
 Filed July 16, 1963, Ser. No. 295,473
 1 Claim. (Cl. 139—84)

This invention relates to improved means for connecting the doby jack and harness frame of a loom. More particularly, the invention is an improved doby loop, sometimes termed a jack eye.

Numerous types of doby loops are known in the prior art, most of which are formed of metal and frequently include movable or detachable portions to facilitate connecting the doby loop with the leader wire or cord which in turn passes over sheaves and is connected with the harness frame of the loom. Some prior art doby loops have rollers or like means at one or both ends thereof to reduce friction. Generally, these prior art devices are too bulky, too costly and sometimes impractical. A need still exists in the art for an improved doby loop, and one which overcomes the aforementioned deficiencies and at the same time is extremely economical to manufacture and install. Another common deficiency of the prior art resides in the fact that known doby loops are not symmetrical or reversible end-for-end, thereby requiring some degree of knowledge and skill to install properly and frequently resulting in loss of time and improper functioning of the loom. In this last respect, one of the main objects of the invention is to provide a unitary or one piece completely symmetrical doby loop which is reversible so that either end thereof may be attached to the doby jack or leader wire and therefore no special skill or knowledge is required for proper installation and there is no chance for improper functioning of the loop once installed.

Another object is to provide a doby loop which may be molded from nylon, plastic or other self-lubricating materials and which may be extremely slender and symmetrically tapered at both ends to reduce the possibility of interference or "hanging up" with adjacent loops arranged in side-by-side relation on the multiplicity of jacks found on the loom.

Other objects and advantages of the invention will be apparent or will be mentioned during the course of the following description.

In the accompanying drawings forming a part of this application and in which like numerals are employed to designate like parts throughout the same,

FIGURE 1 is a partly diagrammatic side elevation of my improved doby loop installed upon a loom,

FIGURE 2 is a perspective view of the doby loop according to one preferred embodiment thereof,

FIGURE 3 is a longitudinal vertical section taken on line 3—3 of FIGURE 2,

FIGURE 4 is a perspective view of a doby loop according to a slight modification of the invention, and

FIGURE 5 is a longitudinal vertical section taken on line 5—5 of FIGURE 4.

In the drawings, wherein for the purpose of illustration are shown preferred embodiments of the invention, attention is directed first to FIGURES 1 through 3, wherein the numeral 10 designates the frame of the loom, upon which are mounted sheaves 11 for receiving and guiding leader wires or cords 12 having their ends secured to eyes 13 on the usual harness frames 14. The numeral 15 designates one of a number of doby jacks and it will be understood that a plurality of these jacks operate in closely spaced relation in conjunction with the harness mechanism, as is well known.

My improved doby loop 16, FIGURES 1-3, is preferably formed of compressed fiber or the like and is unitary,

2

as shown. The doby loop 16 is rectangular in cross section and elongated and is provided with a through slot 17, the rounded ends 18 of which are symmetrical and spaced equidistantly from the ends 19 of the doby loop which are symmetrically tapered and substantially V-shaped, as shown. The side wall portions 20 adjacent slot 17 are formed as thin as possible for maximum clearance between adjacent loops during operation, and the slot 17 is formed only sufficiently wide to accommodate the notched upper end of the jack 15. The doby loop 16 is smooth surfaced and free of burrs or rough spots and may be formed as depicted in FIGURES 2 and 3 by machining a section of compressed fiber.

As will be quite obvious from an inspection of the drawing, the doby loop 16 being symmetrical is completely reversible as far as installation is concerned relative to the jack 15 and leader wire 12. One end of the slot 17 receives the bend 21 of the leader wire and the other end of the slot receives the top of the doby jack 15 having the curved notches 22. The slot 17 is sized to accommodate the doby jack and one of its notches with a minimum of friction and with stability. The doby loop is strong, self-lubricating and easy to install and is reversible and symmetrical, as stated. The tapered substantially V-shaped ends 19 and the slender construction of the doby loop substantially precludes rubbing or interference with adjacent doby loops on the loom. The device is reliable, efficient and long-lasting in operation and extremely economical to manufacture and install.

FIGURES 4 and 5 show a slight modification, wherein the doby loop 23 is preferably formed by molding from nylon, plastic or like self-lubricating material. The construction is generally similar to that of doby loop 16 and need not be repeated in detail but there are certain refinements. By virtue of the molding operation, the end walls of the through slot 24 may be smoothly rounded at 25 to further reduce friction and to fit smoothly with the notches 22 of the jack 15 and the leader wire 12, as shown in FIGURE 1. The end walls of the slot 24 are rounded on radii whose axes are substantially perpendicular to the sides of the slot and centered midway between the sides of the doby loop having the slot opening therethrough, as illustrated in FIGURE 5. In all other respects, the molded doby loop is substantially the same and possesses the same advantages enumerated above for the invention generally and in connection with the prior embodiment shown in FIGURE 2. As in the prior form of the invention, the opposite ends of the doby loop 23, FIGURES 4 and 5, are tapered and substantially V-shaped. Due to the molding operations, there may be some slight differences in the dimensions and configuration of the doby loop 23 as compared to the doby loop 16 but in all critical respects, the two forms of the invention are the same and function in the identical manner to achieve the mentioned objectives while on the loom.

By way of summation and comparison with the prior art, the instant doby loop in either disclosed form thereof is smaller in overall dimensions, lighter and cheaper to make. It is self-lubricating, symmetrical or reversible, and therefore time-saving in installation. The tapered ends prevent interference with adjacent loops as stated. The doby loops fit accurately and smoothly with the leader wires and doby jacks.

It is to be understood that the forms of the invention herewith shown and described are to be taken as preferred examples of the same, and that various changes in the shape, size and arrangement of parts may be resorted to, without departing from the spirit of the invention or scope of the subjoined claim.

Having thus described my invention, I claim:

A one-piece molded nylon doby loop which is sym-

metrical and therefore reversible during installation or use, said dobby loop being substantially rectangular in cross section and elongated and having a centrally disposed longitudinal slot formed therethrough between opposite sides thereof, said slot extending for a major portion of the length of the dobby loop and terminating equidistantly from the ends thereof, said slot having opposite end walls which are smoothly rounded on radii whose axes are substantially perpendicular to the sides of the slot and centered midway between the sides of the dobby loop having the slot opening therethrough, and substantially V-shaped oppositely facing tapered ends on the dobby loop whose sides constitute continuations of the sides of the dobby loop between which the slot is formed.
